BOBBIN-CONTROLLING DEVICE.

1,181,160.

Specification of Letters Patent.

Patented May 2, 1916.

Application filed May 11, 1914. Serial No. 837,661.

To all whom it may concern:

Be it known that I, WILLIAM N. PARKES, a citizen of the United States, residing at Brooklyn, in the county of Kings and State 5 of New York, have invented certain new and useful Improvements in Bobbin-Controlling Devices, of which the following is a specification, reference being had therein to the accompanying drawings.

10 In my patent applications Serial Nos. 835,843 and 835,844, filed May 2, 1914, I have shown a loop-taker comprising a rotary loop-seizing member having a thread-case journaled therein and provided with an es- 15 capement device for restraining the same against rotation while permitting the needle-thread loops to be freely cast about the lower thread. The thread-case of the said applications is provided in the usual 20 manner with a tension device acting upon the lower thread drawn from the bobbin.

In certain classes of work, and under cer- 25 tain conditions, it has been found undesir- able to apply a continuous tension to the lower thread, and my present invention has 30 for its object to dispense with such constant tension and to apply a yielding resistance to the delivery of the bobbin-thread only at certain stages of the stitch-forming cycle, 35 and particularly during the setting of the stitches.

In the preferred embodiment of the pres- 35 ent improvement, the bobbin-case holder, comprising a rocking yoke with conver- 40 gently directed fingers at the extremities of its component arms for alternate engage- 45 ment with the bobbin-case, has yieldingly mounted thereon a bobbin-controlling finger adapted to periodically enter the bobbin- 50 cavity of the thread-case for engagement with the rim of the bobbin-flange. By this means a yielding resistance is offered to the rotation of the bobbin, and hence a drag is 55 imposed upon the lower thread under the action of the take-up upon the upper thread in setting the stitches.

The invention will be understood by refer- 60 ence to the accompanying drawings, in which—

50 Figure 1 is an elevation of a part of the sewing machine containing the stitch-form- 55 ing mechanism, partly in section; and Fig. 2 is a front end elevation of the same with the bed-plate in transverse section. Fig. 3 is an end elevation showing the loop-taker and

the bobbin-case holder and bobbin control- 60 ling arm. Fig. 4 is a perspective view of the bobbin controlling arm. Fig. 5 is a sec- 65 tional elevation on line 5—5 of Fig. 1 showing the actuating means for the bobbin-case holder and bobbin controller.

The machine is shown constructed with the usual bed-plate 1 beneath which is jour- 70 naled the rotary loop-taker shaft 2 upon the forward end of which is fixed the cup- 75 shaped loop-seizing member 3 formed with the beak 4 and provided with a central thread-cavity in which is journaled the bob- 80 bin-case 5. The bobbin-case is constructed with an axial thread-cavity having disposed 85 centrally thereof the bobbin-sustaining post 6 upon which is journaled a well known form of disk-bobbin formed with a tubular hub portion and end-flanges 7, being con- 90 fined in position thereon by the latch 8. 75

The outer end of the thread-case is pro- 95 vided with the forwardly projecting lugs 9 having transverse notches 10 adapted to be entered by the convergently arranged and 100 opposed fingers 11 of the rocking escape- 105 ment yoke 12 which receives a rocking movement for each rotation of the loop-seiz- 110 ing member or hook 3. This yoke consti- 115 tutes, in conjunction with the notched lugs 9, an escapement by means of which the 120 thread-case is restrained against rotation with the hook in a manner well known, the 125 fingers 11, which are arranged concentri- 130 cally with the axis of motion of the yoke, 135 being alternately retracted so as to permit 140 the free passage of the needle-thread loops in 145 the loop-casting operation. As represented 150 in the drawings, a loop-guard flange 13 sus- 155 tained by the bobbin-case is formed with an 160 opening 14 through which one of the fingers 165 11 of the yoke moves in performing its 170 function.

As represented in Fig. 1, the bearing 175 member 15 depending from the bed-plate 100 has secured therein by means of the set- 180 screw 16 the tubular bearing sleeve 17 hav- 185 ing bushings 18 in its opposite ends in 190 which is journaled the tubular rock-shaft 19 which is provided at its forward end with 195 the flange 20 to which is rigidly secured the 200 yoke 12.

Fixed within the rearward end of the 205 rock-shaft 19 is the bushing 21 having fitted 210 therein the rearward end of a second rock- 215 shaft 22 having secured upon its forward 220

end by the transverse pin 23 the plug 24 provided upon its outer extremity with the transverse tongue or rib 25. Secured upon the forward end of the plug 24 by means of the screw 26 is the hub 27 of the curved bobbin-controller arm 28, the hub 27 being formed with a transverse notch or groove 29 entered by the rib 25 of the plug 24. The bobbin-controller arm 28 is provided upon its outer extremity with the backwardly extending lip 30 beveled at 31 upon the edge toward which the needle-thread loops are carried by the hook, or at the left as viewed from the front of the machine.

15 The inner rock-shaft 22 is confined against endwise movement at one end by engagement of the hub 27 with the adjacent face of the yoke 12 and at the other end by engagement of the washer 32, secured there-
20 to by the screw 33, with the end of the bushing 21. The two rock-shafts are resiliently connected together by means of the spring 34 surrounding the inner rock-shaft and having one end secured in the bushing 21 and the other in the plug 24, a stop-pin 35 engaging the controller arm 28 in opposition to the spring in the retracted position of said arm, as represented in Fig. 3.

Secured upon the rearward end of the 30 tubular rock-shaft 19 by means of the clamp-screw 36 is the split hub 37 of a crank-arm 38 formed with a forked extremity 39 within which is fitted the slide-block 40 transversely apertured to fit the actuating eccentric 41 upon the loop-taker shaft 2. By this means the rock-shaft 19 receives an oscillation for each rotation of the loop-taker shaft.

In the operation of the machine, the 40 needle 42 depends through the throat-plate 43 and presents a thread-loop which is seized by the hook and carried backwardly and downwardly around the bobbin-case, the yoke 12 being rocked to the left, as represented in Fig. 2, to permit the free passage of the thread-loop, while the finger 11 at the opposite side of the bobbin-case remains in engagement with the latter to detain it against rotation. In this position of the 45 parts, the side-face of the lip 30 of the bobbin-controller which enters a depression 5' in the outer end of the bobbin-case, rests in contact with the rim of the bobbin-stange 7 under the action of the spring 34 and im-
55 poses a yielding resistance to the rotation of the bobbin. As the beak 4 of the hook continues its movement beyond cast-off position, as represented in Fig. 2, and passes beneath the loop-guard 13, the yoke 12 is 60 rocked toward the front of the machine, as represented in Fig. 3, thereby retracting the holding finger 11 at that side and advancing the other of said fingers into operative engagement with the bobbin-cases. In this 65 movement of the yoke, the stop-pin 35 en-

gages the controller-arm 28 and retracts the same from engagement with the bobbin in opposition to the spring 34, whereby a free passage is afforded for the needle-thread loop in being drawn by the take-up.

70

The present machine, as represented in the drawings, is one in which the hook performs two rotations for each reciprocation of the needle, and in the succeeding rotation of the hook the described movements of the thread-case holding yoke 12 and the bobbin-controlling arm 28 are repeated.

75

In my Patent No. 875,613, of Dec. 31, 1907, a friction device applied directly to the side-face of the bobbin is shown applied to a machine constructed with a rotary hook turning upon a vertical axis. Such construction is obviously unadapted for employment in a machine of the present form wherein the hook turns upon an axis disposed transversely to the direction of reciprocation of the needle and the present improvement is designed particularly for embodiment in a rotary hook machine of the latter type. The specific construction and arrangement of the component parts of the present bobbin-controlling means are evidently not material to the present invention, and may be considerably modified within its scope.

80

Having thus set forth the nature of the invention, what I claim herein is:—

85

1. In a sewing machine, the combination with a rotary loop-seizing member, and a bobbin-case journaled therein and formed with an axial bobbin-cavity to receive a bobbin, of a bobbin-controlling member disposed wholly at one side of the bobbin-cavity and movable toward and from said axis for engagement with the rim of the bobbin in said cavity, and actuating means therefor.

90

2. In a sewing machine, the combination with a rotary loop-seizing member, and a bobbin-case journaled therein and formed with an axial bobbin-cavity to receive a bobbin, of a reciprocatory holder for restraining the bobbin-case against movement with the loop-seizing member, and a bobbin controller operatively connected therewith and adapted for yielding engagement with a bobbin contained in said bobbin-cavity.

95

3. In a sewing machine, the combination with a rotary shaft, a loop-seizing member thereon, and a bobbin-case journaled in said member and formed with a cavity to receive a bobbin, of a rock-shaft disposed parallel with said rotary shaft, a bobbin-controller yieldingly sustained by said shaft and adapted to engage said bobbin, and actuating means for said rock-shaft.

100

4. In a sewing machine, the combination with a rotary shaft, a loop-seizing member thereon, and a bobbin-case journaled in said

105

110

120

125

130

member and formed with a cavity to receive a bobbin, of a tubular rock-shaft, a bobbin-case holder secured thereon and adapted to engage the bobbin-case for restraining it against rotation, a second rock-shaft journaled within the tubular rock-shaft, a bobbin-controlling arm fixed thereon and adapted to enter the bobbin-case cavity to engage the bobbin, a resilient connection between said rock-shafts, and actuating means for said tubular rock-shaft.

4. In a sewing machine, the combination with a rotary shaft, a loop-seizing member thereon, and a bobbin case journaled in it said member and formed with a cavity to receive a bobbin, of a tubular rock-shaft, a bobbin-case holder secured thereon and

adapted to engage the bobbin-case for restraining it against rotation, a second rock-shaft journaled within the tubular rock-shaft, a bobbin-controlling arm fixed thereon and adapted to enter the bobbin-case cavity to engage the bobbin, a spring surrounding the second-named rock-shaft and connected at opposite extremities with said rock-shafts, respectively, and actuating means for said tubular rock-shaft. 20 25

In testimony whereof, I have signed my name to this specification, in the presence of two subscribing witnesses.

WILLIAM N. PARKES.
